Patented Mar. 13, 1917.

UNITED STATES PATENT OFFICE.

JOHN F. CURRIVAN, OF BROOKLYN, NEW YORK.

ENVELOP.

1,219,260.

Specification of Letters Patent. Patented Mar. 13, 1917.

Application filed April 13, 1915. Serial No. 21,040.

To all whom it may concern:

Be it known that I, JOHN F. CURRIVAN, a citizen of the United States, residing in the borough of Brooklyn, in the county of 5 Kings and State of New York, have invented a new and useful Improvement in Envelops, of which the following is a specification.

My invention relates to an improved envelop, of that class that is adapted to be 10 used for commercial use, one which will hold its contents of whatsoever character safe even in the transmission through the mail.

An object of the invention is to provide an envelop of a single piece of material, which 15 may be formed in the shape of a tube, then flattened and cut into the desired lengths for the envelops, then so forming the material at the open end to become interlocked in such a manner as to permit of the same being 20 readily opened and closed.

Another object of my invention is to provide an envelop that has no openings that lead within the inclosure, and at the same time has its interlocking means approximately at the top. The envelop when closed 25 will transmit its contents safe, and by reason of its construction and arrangement provides for the ready opening of the same.

Another object of the invention is that 30 such envelop may be made automatically from a single piece of material, thus permitting the same to be made in quantity, such parts being so formed and secured that the same may be done by a continuous operation. The design shown herein is simple 35 in its construction, and in view of the simplicity and security of the herein shown locking means, it is sure to recommend itself over the metallic or other fasteners.

40 Other objects will appear during the course of this description, and with them in view, the invention consists in the parts, features and combinations of elements for making a secure closure as hereinafter described and pointed out in the claims.

In the drawings is shown the preferred 45 form of locking means for the open end of the envelop, such drawings forming part of this specification, in which like reference 50 characters designate like parts throughout the several views.

Figure 1 shows the open end of an envelop after being cut, and the first fold made to form the pocket;

55 Fig. 2 shows the reinforced tongue of the envelop, with the folded over portion of the

pocket, scored and pasted in position along its outer edge;

Fig. 3 shows the tongue folded over on top of the pocket, the scored portion folded 60 over upon the same ready to receive the final fold to interlock the parts, and

Fig. 4 shows the end of the envelop when the last fold has been made, and the same 65 is ready for the mail.

Fig. 5 is a sectional view showing a modification of the closure flap.

Fig. 6 is a view in elevation of a modification of the flap end reinforcement.

Envelops, packages or other receptacles 70 may be made in various shapes or forms, but for a clear understanding in the present instance the invention is disclosed in the form of an ordinary envelop such as is used for the transmission of catalogues, samples, 75 and other such articles through the mail. In

the present instance it is preferred as before noted to manufacture the envelops automatically, to do this it is desired first to form a tube of the material, and then after 80 pasting it, flatten the same, then to cut into desired lengths. The diameter of the envelop is shown at 5—6, where it receives its first cut, at or about the same time it receives the other cuts 7 and 8 to form the tongue 9, 85 the tongue is scored at 10 with the cut portion 11, which forms the mouth of the envelop. The part 11 which before being folded over on the line 10, extended to the top of the tongue as per the dotted line, but 90 now as folded over upon the body portion 12 of the envelop, when pasted at its outer sides, forms a pocket with lines 13, 14 and 15 scored on one side, forming a folding member of the sides 16 and 17, while the part 95 18 is pasted to the side of the envelop. The other side of the pocket is also scored in like manner at 19, 20 and 21, forming a folding member on this side of the envelop of the sides 22 and 23, the part 24 being pasted 100 or otherwise secured to the edge 25, while the edge of the flap 18 is secured to the edge 26 of the envelop. Thus it will be seen that the pocket as formed, has the parts 16—17, and 22—23, so shaped to permit their being 105 thrown toward or from the center, and at a point where the points of the folding members meet, the parts here are scored as at 29, which permits of these parts being further interlocked as will be noted farther on.

When it is desired to close the envelop,

the folding members 16—17 and 22—23 are thrown back on the pieces 18 and 24, and the tongue 9 is brought over and laid upon the pocket 11, then the folders 16—17 and 22—23 are brought over on top of the tongue 9, as is shown in Fig. 3, then to further interlock these several members together the parts are turned under on the scored line 28 on the tongue, and 29 on the pocket portion 11. Thus it will be seen that the closure is made perfect by reason of the several members being all interlocked and held secure therein by reason of the friction of the surfaces of these several parts. To this point it has only been explained how to close the envelop in a secure manner, while this is a very essential object of all such envelops, yet it is also a very essential object to be able to open the same as readily, and to do this all that is necessary is to pull upwardly at the points the folding members, which will then have the tendency of pulling out of the pocket the upwardly tucked end of the several members; no further effort is required to open the envelop. Of all such envelops on the market none is so simple in construction, nor perfect in their locking means as the one shown herewith, which has been tested and found to hold the contents secure.

As shown, the tongue may have a reinforcement thereon in the form of a strip 27, which may be secured in any suitable way. This reinforcement is desirable when the contents of the envelop are heavy, and by constant throwing about or handling in transportation the under fold may under these circumstances, where the tongue is not reinforced, cause the same to be pulled out from the pocket, and then cause the contents of the envelop to get out of the same, but where the reinforcement is used, then there is not the slightest danger that such will happen, because this reinforcement prevents the end from coming out of the pocket, unless the folding members are so exerted upon as to positively extricate the same from the pocket.

It will be understood that envelops have been made of many different styles wherein the tongue is brought over the top and then turned up in a pocket, to distinguish it from that class which has a slit in the envelop and extends the tongue therein, and again in that where the tongue is brought under a staple and bent up. All such forms, together with that of having a small tape along the edge of the pocket, belong practically to the same class, as it is the tongue, and the tongue only that requires all possible reinforcements and interlocking means to prevent the tongue from becoming disengaged from its locking means. It is also understood that envelops, bags or

any other shaped receptacle may be provided with the same locking means. But, of course, it is more adapted for use for circulars, catalogues, samples and other commercial uses, where the contents can be readily and securely inclosed by the sender, and adapted to be opened just as easily by the recipient, yet not be objected to by the Post Office Department as is very often the case with receptacles closed by metallic fastenings.

Having now described the preferred form in which it is believed the invention is adapted, it will be understood that those skilled in the art to which this invention belongs, can vary the closure and locking means without departing from the essentials of the invention described, as all such modifications would necessarily fall within the purview of the present invention.

In Fig. 5 is shown a modification, the details of which will be explained farther on.

This modification shows an extra flap formed on the envelop which is particularly useful where it is desired to inclose finely divided material in the envelop, as it is necessary to have a secure fastening on the envelop to retain the material within. So as to give extra strength and retaining qualities, the transverse portion 11, forming the pocket, is slit or cut, as indicated at 30 and 31 Fig. 1, and is also slit transversely, as indicated by the line 32, to form the flap or tongue 33. After the material has been deposited within the envelop, the flap 33 can be folded over between the two walls of the body portion, as seen most clearly in Fig. 5, permitting the main flap 9 to be folded over and to be engaged by the parts, as before described, before finally making the last and complete fold to lock the envelop for transit.

By providing this additional flap 33, none of the advantages heretofore described are lost, in fact this flap aids materially in retaining the contents within the envelop. Again, by use of this additional flap 33, the top or closure of the envelop will be materially strengthened.

In Fig. 6 is shown a reinforcing strip 27' which is a modification of the strip 27. The strip 27' may be cut from the blank from which the envelop is cut and folded back upon the portion 9, to which it is pasted or glued, or it may be formed of a separate piece which is pasted on the portion 9. The sole purpose of this reinforcement is to add strength to the tip of the flap or tongue 9.

What I claim as new is:

1. In an article of the class described, the combination of a body, a portion formed integral with the wall at one side of the body and turned back upon the body to form a pocket and an extending portion, said por-

- tion being provided with a flap, and a flap on said body portion positioned to fold first over then into the pocket with its end entering with the extending portion.
- 5 2. In an article of the class described, the combination of a body portion, a portion having a turned under part and formed integral with the wall on one side of said body to provide a pocket, lateral wings on said portion and located at the sides thereof, said wings being secured to said body, a flap for said body positioned to fold first over and then into the pocket, and members interposed between the wings and the said portion and integral therewith positioned to fold first over the flap and then with the flap into the pocket.
- 10 3. In an article of the class described, the combination of a body, a portion having a turned under part and formed integral with the wall on one side of said body to provide a pocket, lateral wings forming integral parts of said portion and located at the ends thereof, said wings being secured to said body, a flap on said portion and positioned to enter the pocket, and a flap of said body portion positioned to fold first over and then into the pocket.
- 15 4. In an article of the class described, the combination of a body, a flap forming a continuation of the wall on the other side of said body to form a pocket, a flap on said portion and positioned to enter the pocket, and a flap integral with said portion and located between the ends thereof, positioned to fold over the first named flap and having a portion positioned to enter the pocket therewith.
- 20 5. In an article of the class described, the combination of a body, a portion formed integral with the wall on one side of said body and turned back upon the body to form a pocket, a flap for said body positioned to fold first over and then into the pocket, and a flap engaging members formed on said portion and positioned to fold upon the flap when the flap is folded over the pocket.
- 25 6. The combination of a body, a flap forming a continuation of the wall on one side of the body, and a portion forming a continuation of the wall on the other side of said body turned down and secured to said body at the sides of the body and having an intermediate portion free and forming with said body a pocket, a part of said intermediate portion being formed and positioned to receive said flap and fold into the said pocket.
- 30 7. The combination of a body, a flap forming a continuation of the wall on one side of the body, and a portion forming a continuation of the wall on the other side of said body secured at the sides of the body and having an intermediate portion free and forming with said body a pocket, a part of said intermediate portion being formed and positioned to receive said flap and fold into the said pocket.
- 35 8. The combination of a body, a flap forming a continuation of the wall on one side of the body, and a portion forming a continuation of the wall on the other side of the body secured at the sides of the body and having an intermediate portion free and forming with said body a pocket, a part of said intermediate portion being formed and positioned to receive said flap and fold into the said pocket therewith, the said flap and first named portion being formed of an extension of the body portion and said secured portion provided with a second flap adapted to be folded as described.
- 40 9. The combination of a body, a flap forming a continuation of the wall on one side of the body, and a portion forming a continuation of the wall on the other side of the body secured at the sides of the body and having an intermediate portion free and forming with said body a pocket, a part of said intermediate portion being formed and positioned to fold over said flap and fold into the said pocket therewith.
- 45 10. The combination of a body, a flap forming a continuation of the wall on one side of the body, and a portion forming a continuation of the wall on the other side of said body turned down and secured to said body at the sides of the body and having an intermediate portion free and forming with said body a pocket, a part of said intermediate portion being formed and positioned to receive said flap, and said flap positioned to fold over the first named portion provided with a supplemental flap and then into the pocket.
- 50 11. The combination of a body, a flap forming a continuation of the wall on one side of the body, and a portion forming a continuation of the wall on the other side of said body turned down and secured to said body at the sides of the body and having an intermediate portion free and forming with said body a pocket, a part of said intermediate portion forming a supplemental flap while the balance is formed and positioned to receive the first mentioned flap, and said flap positioned to fold over the first named portion and the supplemental flap and then into the pocket.
- 55 12. The combination of a body, a flap forming a continuation of the wall on one side of the body, and a portion forming a continuation of the wall on the other side of the body secured at the sides of the body and having an intermediate portion free and forming with said body a pocket, a part of said intermediate portion being formed and positioned to receive said flap and fold into the said pocket.
- 60 13. The combination of a body, a flap forming a continuation of the wall on one side of the body, and a portion forming a continuation of the wall on the other side of said body secured at the sides of the body and having an intermediate portion free and forming with said body a pocket, a part of said intermediate portion being formed and positioned to receive said flap and fold into the said pocket.

positioned to fold over said flap and fold into the said pocket therewith, and a part of said intermediate portion near the end of the body wall being severed from the first 5 named portion and formed and positioned to be turned in between the two walls of said body.

In testimony whereof, I have signed my name in the presence of subscribing witnesses.

JOHN F. CURRIVAN. [L.S.]

Witnesses:

J. B. McGIRR,

THOMAS E. WILLARD.
